UNITED STATES PATENT OFFICE.

FRED WILKIE, OF NEW YORK, N. Y., ASSIGNOR TO THE DRESSEL RAILWAY LAMP WORKS, A CORPORATION OF NEW YORK.

SIGNAL-LAMP.

1,106,690.

Specification of Letters Patent. Patented Aug. 11, 1914.

Application filed September 9, 1908. Serial No. 452,295.

To all whom it may concern:

Be it known that I, FRED WILKIE, a citizen of the United States, residing at the city of New York, borough of Bronx, in the county and State of New York, have invented certain new and useful Improvements in Signal-Lamps, of which the following is a full, clear, and exact specification.

My invention relates to improvements in signal lamps, and the same has for its object more particularly to provide a signal lamp having a plurality of signal glass holders therein which are adapted to be thrown individually into position between the lens and the lamp.

Further, said invention has for its object to provide a signal lamp having a plurality of signal glass holders which are so constructed and arranged that the shifting of one of the signal glass holders into operative position will automatically lock the remaining signal glass holder or holders in inoperative position.

Further, said invention has for its object to provide a supporting means for the signal glass holders and the automatic locking device therefor, which may be bodily set into a lamp and secured thereto in order to maintain the same in position to be operated from without the lantern casing.

To the attainment of the aforesaid objects and ends my invention consists in the novel details of construction, and in the combination, connection and arrangement of parts hereinafter described, and then pointed out in the claims.

In the accompanying drawings forming part of this specification, wherein like numerals of reference indicate like parts, Figure 1 is a side view partly broken away and in section, showing one form of signal lantern constructed according to and embodying my invention. Fig. 2 is an enlarged detail horizontal sectional view showing the signal glass holders and the locking means therefor in top view; Fig. 3 is an enlarged detail side view showing the supporting means and locking device for the signal glass holders, one of said signal glass holders being shown in operative position, and the other locked to its inoperative position; Fig. 4 is a section taken on the line 4-4 of Fig. 3, looking in the direction of the arrow, and Fig. 5 is an end view of the parts shown in side view at Fig. 3.

In said drawings 10 designates a lantern casing of usual general construction provided with a sliding door 11, and at two of its sides with lenses 12 12 mounted in cones 13 13 arranged at right angles to each other, 60 and 14 denotes a lamp supported in the base of the lantern. To one side of each lens cone upon the inner surface of the lantern casing 10 is secured a bracket 15 having a centrally located upwardly extending rigid 65 supporting arm 16 provided at its upper end with a bearing 17. To each side of said rigid supporting arm 16 are arranged upwardly projecting short arms or bearings 18 18.

19 19 denote signal glass holders each having an arm 20 extending therefrom which is arranged intermediate one of the bearings 18 18 and the arm 16, and pivotally mounted upon a screw or rivet 21 passing 75 through both of said arms 20, 20, the bearings 18, 18 and the arm 16. To the other or projecting ends of the arms 20 20 are pivotally secured links 22 22 having their ends bent at right angles thereto to form finger 80 portions 23 23. The extreme ends of the arms 20 20 are provided with semicircular recesses to receive the free ends of springs 24, 24 which are secured at their lower ends to the bracket portion 15. The springs 24 85 24 are provided adjacent to their free ends with offset portions 25 25 which are adapted to engage the recessed free ends of the arms 20 20 in order to maintain the signal glass holders 19 19 to their operative or inoperative positions.

27 denotes a locking device consisting of a substantially rectangular oscillating link member 28 which normally embraces the arms 20 20 of both signal glass holders when 95 the same are raised or adjusted to their inoperative positions. The said link member is pivotally suspended from its upper edge upon a screw 29 secured in one end of the bearing 17 on the arm 16, and has its lower end split, and its ends 30 30 inclined downwardly toward each other, and separated only enough to receive one of the arms 20 of the signal glass holders at one time, which is adapted to rest upon the inclined 100 portion or stop 31 of the bracket 15.

32 32 denotes housings which are secured to the outer surface of the lantern casing and inclose the projecting portions of the brackets 15 15 and parts carried thereby. Said 110

housings 32 32 are provided at their lower ends with apertures through which the ends of the link members 22 22 normally extend.

The operation of the apparatus is as follows: In order to display a colored signal glass it merely becomes necessary to press one of the links 22 upwardly into the housing 32 by means of its finger portion 23 thereby elevating the projecting end of one of the signal glass arms 20 connected thereto, and causing the forward end of said arm which carries the signal glass to move downwardly, until its lower edge engages the inner inclined edge of the link 28 and passes into the opening or split in said link and contacts with the inclined surface or stop 31 on the bracket 15, thereby limiting the downward movement of said arm and the lens holder carried thereby. As soon as the arm 20 has come into engagement with said inclined portion or stop 31 the colored signal glass will be in position intermediate the lamp and the lens of the lantern and impart to the light projected through the lens the color desired. By the movement of one signal glass holder into operative position intermediate the lamp and the lens, the remaining signal glass holder will be held to its inoperative position, this result being due to the fact that the slit in the bottom of the link 28 is only wide enough to accommodate the arm of one glass holder at a time. As the arm of one glass holder enters said slit the link 28 will be moved to one side or the other, and in so doing one of the inclined ends 30 of said link will be brought into contact with the lower edge of the arm 20 of the inoperative signal glass holder and prevent the same being lowered until the glass holder then in operative position has been freed of its engagement with the slit in the link, and again raised to its inoperative position.

Having thus described my invention, what I claim and desire to secure by Letters Patent is:

1. In a signal lamp the combination of a bracket, a vertical member thereon, signal glass holders pivotally mounted on said member, means for actuating said signal glass holders, a member pivotally mounted on said vertical member and embracing said signal glass holders intermediate of their ends for locking one of said signal glass holders in inoperative position as the other of said signal glass holders is moved into operative position, and means carried by said bracket for positively maintaining said signal glass holders to their operative and inoperative positions, substantially as specified.

2. In a signal lamp the combination of a bracket, a vertical member thereon, bearings on said bracket, signal glass holders pivot-

ally supported upon said bearings, means for actuating said signal glass holders, a member pivotally mounted on said vertical member and embracing said signal glass holders intermediate of their ends for locking one of said signal glass holders in inoperative position as the other of said signal glass holders is moved into operative position, and means carried by said bracket for positively maintaining said signal glass holders to their operative and inoperative positions, substantially as specified. 75

3. In a signal lamp the combination of a bracket, a vertical member thereon, bearings on said bracket positioned on opposite sides of said member and spaced therefrom, a pin extending through said bearings and said vertical member, signal glass holders pivotally mounted upon said pin on opposite sides of said vertical member, means for actuating said signal glass holders to move them into their operative and inoperative positions, and means carried by said bracket for positively maintaining said signal glass holders to their operative and inoperative positions, substantially as specified. 80 85

4. A signal lamp comprising a casing, a lens mounted therein, a lamp arranged in said casing behind said lens, a housing on said casing, a support secured in said casing comprising a bracket, bearings arranged upon said bracket, an arm extending upwardly from said bracket intermediate said bearings, a bearing at the upper end of said arm, signal glass holders pivotally mounted side by side intermediate said bearings and arm, links arranged in said housing and pivotally connected to said signal glass holders for actuating the same, means for limiting the movement of said signal glass holders, a split link pivotally supported at its upper end in the bearing on said arm and embracing said signal glass holders intermediate their pivoted ends and the signal glasses carried thereby, said link having its ends inclined downwardly toward each other for permitting either of said signal glass holders to enter into operative position intermediate the inclined edges thereof, and preventing the other of said signal glass holders from entering into operative position therein, and spring means engaging the ends of said arms for positively holding the same to their operative and inoperative positions, substantially as specified. 90 95 100 105 110 115

Signed at the city of New York, in the county and State of New York, this 20th day of August, nineteen hundred and eight. 120

FRED WILKIE.
